WIRE-SUPPORTING ARRANGEMENT

Kurt R. Walch, Philadelphia, Pa., assignor to General Electric Company, a corporation of New York

Application October 31, 1956, Serial No. 619,537

6 Claims. (Cl. 248—68)

This invention relates to a wire-supporting arrangement and, more particularly, to a wire-supporting arrangement which comprises a wiring cleat supporting upon a panel or the like a group of insulated wires, either in bundle or cable form.

The invention is specifically concerned with the type of wiring cleat which comprises a wire-supporting surface against which the wires are secured by suitable fastening means. Prior designs of this general type of which I am aware have been subject to a number of disadvantages. For example, in utilizing certain of these prior designs, it has been necessary to resort to unduly time-consuming operations in order to secure the wires to the cleat. Additionally, with most of these prior designs, if the fastening means has become slightly loosened, the wires could become easily detached from the cleat, thus defeating the supporting function of the cleat. Moreover, few of these prior designs have readily lent themselves to being used with a variety of different types of fastening means, and, hence, it has been necessary to stock a variety of cleats where different types of fastening means are to be used. Still further, many of the prior designs, when incorporated into a wiring assembly, have consumed an undue amount of space and have not lent themselves to neat and compact assemblies inasmuch as they have projected laterally outward from the supported wires in an unsightly fashion.

Accordingly, a general object of my invention is to provide a simple and inexpensive wiring cleat which is largely free from the disadvantages set forth above.

Another object of my invention is to provide a wiring cleat which is so constructed that wires can be quickly secured thereto and thereafter prevented from becoming detached even if the wire-fastening means becomes slightly loosened.

Another object is to provide a wiring cleat of the above nature which is concealed beneath the wires it supports and thus consumes a minimum of otherwise-useful space and allows for a neat and compact wiring assembly.

In carrying out my invention in one form, I support one or more wires upon a panel or the like by means of a wiring cleat which has a mounting foot secured against a surface of the panel. Carried by the mounting foot is a body portion which extends generally parallel to the surface of the panel in spaced-apart relationship thereto. The body portion is corrugated to provide alternate ridges and furrows extending transversely thereof. The supported wires extend transversely to these ridges and furrows and are anchored against one side of the body portion by fastening means which encircles the wires and the body portion and interlocks with at least one of the furrows on the other side of the body portion.

For a better understanding of my invention, reference may be had to the following specification taken in connection with the accompanying drawing, wherein:

Fig. 1 is a side elevational view showing a wire-supporting arrangement which utilizes a wiring cleat con-

structed in accordance with one form of my invention.

Fig. 2 is a perspective view showing by itself the wiring cleat which is utilized in the arrangement of Fig. 1.

Fig. 3 is a cross-sectional view taken along the line 5 3—3 of Fig. 1.

Figs. 4 and 5 are side elevational views of modified forms of wire-supporting arrangements which utilize the wiring cleat of Fig. 2.

Fig. 6 shows another modified wire-supporting arrangement which utilizes the wiring cleat of Fig. 2.

Fig. 7 is a cross-sectional view taken along the line 7—7 of Fig. 6.

Fig. 8 shows still another modified wire-supporting arrangement which utilizes the cleat of Fig. 2.

Fig. 9 is a cross-sectional view along the line 9—9 of Fig. 8.

Fig. 10 is an elevational view showing a modified form of wiring cleat.

Referring now to Fig. 1, a plurality of insulated wires 20 12 are shown formed into a bundle and supported upon a panel or base 14 by means of a wiring cleat 15 constructed in accordance with one form of my invention. The cleat 15, comprises a mounting foot 16 which extends parallel to the upper surface of the panel or base 25 14 and is secured to the panel by suitable means, such as, for example, by a screw 17 threaded into the panel. Other securing arrangements such as bolts or welding can equally well be used for this purpose. Carried by the mounting foot 16 is a body portion 18 of strip-like 30 form which is shown laterally offset from the mounting foot. This body portion 18 extends generally parallel to the upper panel surface and is spaced therefrom.

As can be seen in Figs. 1 and 2, the body portion 18 of the cleat is provided with corrugations which form alternate ridges and furrows extending transversely of the body portion on opposite sides thereof. The wires 12 extend transversely of these ridges and furrows and are anchored against the upper surface of the body portion 40 18 by suitable fastening means, such as lacing cord 20, which is bound tightly about the wires 12 and the body portion 18. With the lacing cord 20 located in one of the furrows 21 on the lower side of the body portion and thus interlocking with the furrow, as shown in Fig. 1, slippage of the cord along the length of the cleat is 45 effectively prevented by the adjacent ridges, even if the cord should become slightly loosened. So long as the cord 20 remains reasonably tight, the bundle of wires is firmly anchored to the cleat and effectively prevented from moving in any direction with respect to the cleat.

Assuming that the cleat first has been secured to the panel 14, anchoring of the wires 12 upon the cleat can be a quick and simple operation with the illustrated cleat. For example, all that is involved is first forming the 55 wires 12 into a bundle, resting the bundle upon the upper surface of the body portion 18, then winding the lacing cord 20 about the bundle and the body portion with the cord located in the furrow 21, after which the lacing cord is pulled tight and suitably tied. The space provided 60 between the body portion 18 and the panel 14 greatly facilitates the winding operation inasmuch as it allows the assembler to slip the cord beneath the cleat from its front end 22 as he winds the cord about the bundle and cleat.

The laterally offset relationship of the body portion 18 with respect to the mounting foot 16 not only serves to provide the above-described spacing between the panel 14 and the body portion 18 but also serves to protect the insulation of the lower wires 12 from being abraded 65 by the head of screw 17. Because the heads of screws such as 17 sometimes develop sharp burrs adjacent their tool-receiving slots, they are capable of seriously impair-

ing this insulation if the wires are allowed to bear firmly against such heads. The offset between my mounting foot 16 and body portion 18 locates the wires 12 in such a position that their insulation does not contact the head of screw 17 with sufficient pressure to allow damage to such insulation. If desired, the offset can be of sufficient extent to insure that the wires are maintained completely out of contact with the screw head.

It will be apparent that the above-described laterally offset relationship between the foot 16 and the body portion 18 is also advantageous in those applications in which the foot is arc-welded to the panel. Such arc-welding tends to produce sharp edges projecting upwardly slightly from the foot 16, and the offset acts to maintain the supported wires out of damaging contact with such edges.

From Figs. 1 and 3 it will be apparent that the insulated wires 12 are generally in alignment with the cleat 15 along its length, and thus the cleat is largely concealed beneath such wires when viewed from above. This relationship not only contributes to a neat wiring assembly but also contributes to a highly compact assembly inasmuch as the cleat does not project laterally outward from the bundle of wires to consume otherwise-useful space.

It should also be apparent from Figs. 1-3 that my cleat 15 is capable of supporting any number of wires of the same or varying size so long as the inherent mechanical strength of the cleat or the fastening means is not overtaxed. In this same regard, it is to be noted that my cleat is capable of supporting only a single insulated wire if need be.

An important advantage of my cleat is its versatility in lending itself to use with different types of wire-fastening means. For example, for larger bundles of wires or for cables, stronger and more complex ties of lacing cord can be readily used for anchoring the bundle to the cleat 15. In this regard, reference may be had to Fig. 4 in which the lacing cord 20 is shown bound about the bundle and the cleat in separate spaced-apart locations. As a further example, reference may be had to Fig. 5 in which the cord is shown bound about the bundle and cleat along the entire length of the body portion of the cleat. In any case, when cord is used as fastening means, at least a portion of the cord should be located in at least one of the furrows on the underside of the cleat in order to prevent the cord from slipping with respect to the cleat as described hereinabove.

Figs. 6 and 7 further illustrate the versatility of the cleat in lending itself to use with different types of fastening means. Here, the wires are anchored to the upper surface of the body portion 18 by means of a resilient metallic ring 30 tending to contract about the bundle end cleat. Assuming that the cleat has first been secured to the panel, it is a simple matter to then assemble the ring 30 about the wires and the cleat. For example, the ring is first positioned about the wires 12 at some point spaced from the cleat; it is then expanded by suitably forcing together its ends 31, and, with the ring held in this expanded condition, it is slid along the wires over the front end 22 of the cleat into its proper position about the cleat, after which the ring is allowed to contract into the clamping position shown in Fig. 6.

The illustrated wiring cleat 15 also lends itself to use with suitable banding, such as shown at 35 in Figs. 8 and 9. Assuming that the cleat is attached to the panel, the banding 35 is simply slipped beneath the wires 12 ahead of the cleat, is then slid under the front end 22 of the cleat, after which it is suitably tightened about the cleat and the bundle of wires. The banding 35 is soft enough to conform in a general way with the configuration of the underside of the ridged body portion 18, and this effectively prevents longitudinal movement of the band relative to the cleat. Preferably, the shoulder formed at the front end of the cleat projects slightly below the lowermost surfaces of the other ridges, and this

further insures against objectionable longitudinal movement of the band 35.

In the various embodiments illustrated, the furrows or grooves formed on the top side of the body portion 18 serve the desirable purpose of permitting the free passage of air between the ridge areas upon which the wires 12 are supported. This tends to maintain the insulating cover of the wires 12 free from moisture inasmuch as the air acts to carry away from this region a large portion of the moisture formed by possible surface condensation on the cleat. The grooves themselves also act to drain such moisture away from the insulation.

Another important purpose of the furrows on the upper surface of the body portion 18 is that they allow the cleat easily to be formed from a blank of uniform cross-section, as by a simple stamping process. Since the furrows on the upper surface register with the ridges on the lower surface, and vice versa, the body portion of the cleat is of a generally uniform cross-section along its length, and this allows the stamping operation to be considerably simplified.

Where it is not practical or desirable to mount the wiring cleat 15 directly against the panel or base 14, in the manner shown in Fig. 1, the desired spacing between the body portion 18 and the panel 14 can be obtained even without the offset relationship between the mounting foot 16 and the body portion. For example, in Fig. 10 the mounting foot 16 is provided with a stud 45 secured to the cleat and threaded into the panel 14. This stud 45 supports the mounting foot 16 in spaced-apart relationship to the panel and thereby, provides the desired spacing between the body portion 18 and the panel even though the mounting foot 16 and the body portion 18 are disposed in essentially the same plane. A lock nut 47 threaded on the stud 45 bears against the panel 14 to prevent the cleat from being accidentally shifted with respect to the panel.

While the wiring cleat 15 is preferably formed of metal, it is to be understood that it can equally well be formed of a suitable plastic compound or can be constructed of metal which is covered in whole or part with a plastic compound. These latter constructions would provide additional insulation between the supported wires and the metal panel or base 14.

While I have shown and described particular embodiments of my invention, it will be obvious to those skilled in the art that various changes and modifications may be made without departing from my invention in its broader aspects and I, therefore, intend in the appended claims to cover all such changes and modifications as fall within the true spirit and scope of my invention.

What I claim as new and desire to secure by Letters Patents of the United States is:

1. In an arrangement for supporting one or more wires upon a base, the combination with said base and said wires of a wiring cleat having a mounting foot extending generally parallel to a surface of said base and secured to the base, a body portion carried by said foot and extending generally parallel to said base surface in spaced-apart relationship thereto in a position located between said base surface and said wires, said body portion being provided with corrugations forming alternate ridges and furrows extending transversely of said body portion on opposite sides thereof, and fastening means anchoring said wires against one side of said body portion with the wires extending transversely of said ridges and furrows, said fastening means encircling said wires and said body portion and interlocking with at least one of said furrows on the other side of said body portion.

2. In an arrangement for supporting one or more wires upon a base, the combination with said base and said wires of a wiring cleat having a mounting foot extending generally parallel to a surface of said base and secured to the base, a body portion carried by said foot and extending generally parallel to said base surface in spaced-

apart relationship thereto in a position located between said base surface and said wires, said body portion being corrugated to provide at least one furrow extending transversely of said body portion on one side thereof, and fastening means anchoring said wires against the other side of said body portion with the wires extending transversely of said furrow, said fastening means comprising a binding member encircling said wires and said body portion and having at least a portion thereof located in said furrow.

3. In an arrangement for supporting one or more wires upon a base, the combination with said base and said wires of a wiring cleat having a mounting foot extending generally parallel to a surface of said base and secured to the base, a body portion carried by said foot and extending generally parallel to said base surface in spaced-apart relationship thereto in a position located between said base surface and said wires, said body portion being constituted by a strip of generally uniform cross section throughout its length, the strip being corrugated to provide alternate ridges and furrows extending transversely of the strip on opposite sides thereof, and fastening means for anchoring said wires against one side of said body portion with the wires extending transversely of said ridges and furrows, said fastening means comprising a binding member encircling said wires and said body portion and interlocking with at least one of said ridges on the other side of said body portion. 25

4. The arrangement of claim 3 in which said body portion is disposed in laterally-offset relationship to said mounting foot. 30

5. In an arrangement for supporting one or more

wires upon a base, the combination with said base and said wires of a wiring cleat having a mounting foot extending generally parallel to a surface of said base and secured to the base, a body portion carried by said foot in laterally-offset relationship to said foot and extending generally parallel to said base surface in spaced-apart relationship thereto in a position located between said base surface and said wires, said body portion being provided with corrugations forming alternate ridges and furrows extending transversely of said body portion on opposite sides thereof, and fastening means anchoring said wires against one side of said body portion with the wires extending transversely of said ridges and furrows, said fastening means encircling said wires and said body portion and interlocking with at least one of said ridges or furrows on the other side of said body portion. 15

6. The arrangement of claim 5 in which the laterally offset relationship of said body portion with respect to said mounting foot provides a space between said wires and said mounting foot, a screw for securing the cleat to said panel and having a head which is located in the space between said mounting foot and said wires. 20
